UNITED STATES PATENT OFFICE.

JOSEPH BOUARDAS SMITH BOOTH, OF SIDCUP, ENGLAND, ASSIGNEE TO LANSTON MONOTYPE MACHINE COMPANY, OF PHILADELPHIA, PENNSYLVANIA, A CORPORATION OF VIRGINIA.

TYPOGRAPHIC COMPOSING MACHINE.

Application filed April 26, 1922. Serial No. 556,754.

To all whom it may concern:

Be it known that I, JOSEPH BOUARDAS SMITH BOOTH, a British subject, residing at Shirley House, Main Road, Sidcup, Kent, England, have invented certain new and useful Improvements in Typographic Composing Machines; and I do hereby declare the following to be a full, clear, and exact description of the same, reference being had to the accompanying drawings, forming part of this specification, and to the characters of reference marked thereon.

This invention relates to keyboard machines for composing or preparing record strips, patterns or controllers which are employed to control the action of automatic type casting and composing machines.

The keyboard composing machine to which this invention particularly relates is shown in part in the accompanying drawings and is of the class of machines well known commercially as the product of Lanston Monotype Machine Company and disclosed as to general features in United States Letters Patent No. 944,405 dated December 28, 1909. These machines are well known to those skilled in the art so that a detailed description of their construction and operation is not deemed necessary herein. The keys when operated are adapted to produce signals in the form of perforations in a record strip of paper or the like, which signals usually each comprise two perforations representing a unit, character, symbol or justification fraction. The signal producing devices include a series of punches which by their location coincide with the components of the signal pertaining to the operated key. Certain of these punches are connected with a series of stop bars through which the movement of the punches is communicated to a series of stops forming part of the units measuring mechanism and each denoting a different unit value. The units measuring mechanism registers the value of each signal in a well known manner to aid in ascertaining the justification fraction or the appropriate signal or signals therefor, to complete each line of composition.

In the general organization of the machine the fraction or units necessary to justify a line are added to a certain predetermined "space" body size which is variable setwise as distinguished from "type" bodies with

predetermined or fixed unit values or dimensions, such as characters, points, quads, and the like. It has, however, been proposed for example in United States Letters Patent 1,094,630 dated April 28, 1914, 1,283,958 dated November 5, 1918, 1,307,718 dated June 24, 1919 and 1,307,719 dated June 24, 1919, to provide mechanism whereby the justification fraction can be applied to the normal non-justifiable or fixed dimension "type" bodies.

It may also be pointed out that in keyboard machines of this class one component of the usual signal indicates "position" and the other component "dimension and position" because while the first component indicates a die or matrix position in the casting machine in which the controller is to be used, the second component not only indicates matrix position but also determines and controls the positioning of the normal mold dimensioning mechanism for the selected matrix. This second component is produced by a signal producing member which is coupled with a selected one of the stop bars and stops as previously mentioned so that the line measuring mechanism will record the unit value of the signal to correspond with the unit value of the type body produced under control of this signal. These signal components will be referred to hereinafter as the "position" and "dimensioning" components respectively.

When a space key or space bar is struck between words it produces a signal the dimensioning component of which controls in the casting machine the position of the normal mold dimensioning mechanism as well as the matrix position for casting the space: the other component of a space signal controls the transfer mechanism which effects a change in the value of the normal mold dimensioning mechanism by combining it with the supplementary or justification mold dimensioning mechanism. Thus, the space signal produces in the casting machine a body, the dimension of which is controlled not only by the normal mold dimensioning mechanism placed in position by the dimensioning component of the space signal, but also by the justification mold dimensioning mechanism, the latter having been placed in position by the previous justification signal in the controller. The punch in the

composing machine for producing the transfer component of the space signal is normally connected with a stop bar and stop to register the unit value of the justified space at a fixed amount, usually four units.

With the above mentioned mechanism the dimension indicated for any given position of the normal mold dimensioning devices is two units less when controlled by the 10 dimensioning component of a space signal than when controlled by the like component of a type signal. Co-operating with the mechanism for setting the justification indicating mechanism in accordance with the 15 line remainder is a space number indicator which is operated each time a justification space is recorded.

The principal objects of the present invention are to provide mechanism, capable 20 of being applied to machines in use, for connecting the transfer signal producing mechanism with a selected stop bar and stop of the units measuring mechanism whereby there may be produced a larger minimum 25 justifiable space than and in addition to the usual or normal four units above referred to, and the justification fraction may be added to type bodies. These objects will be more particularly explained hereinafter 30 and other objects and advantages will be pointed out or will otherwise appear in connection with the following description of the device shown in the accompanying drawings and embodying the present invention, in which drawings,

Fig. 1 is a front elevation of a stop bar unit for a typographic composing machine, constructed according to the present invention.

Fig. 2 is a rear elevation of the mechanism of Fig. 1, certain parts being broken away or shown in section.

Fig. 3 is a sectional side elevation on approximately the line 3—3 of Fig. 2 and showing the parts in position for use with normal spaces.

Fig. 4 is a view similar to that of Fig. 2 but with the parts adjusted for use with abnormal spaces.

Fig. 5 is a view similar to that of Fig. 2 with the parts adjusted for adding justification to type bodies.

Fig. 6 is a sectional front elevation of the mechanism of Fig. 5, the cover plate being removed.

Fig. 7 is a sectional plan view of Fig. 4.

Fig. 8 is a sectional elevation showing the punch bars and punches connected with the stop bars and stops, the section through the stop bars being approximately on the line 60 8—8 of Fig. 5.

Fig. 9 is a perspective view of a detail part of the coupling unit.

Fig. 10 is a sectional side elevation showing the mechanism by which the space key

can be used to produce signals having different dimensioning components and,

Fig. 11 is a front elevation of the mechanism shown in Fig. 10.

As a part of the organization of the 70 patented keyboard composing machine illustrated there will be recognized the punch bars 1, (Fig. 8) with their punches 1' and the universal bar 1^a: those punches which produce dimensioning components of sig- 75 nals are connected by means of the levers 3 pivoted on the axis 4, their ends resting in sockets 2 in the punch bars, with the stops 5 through the medium of the stop bars 6, the casing or frame for which stop bars 80 is indicated by the character 7: the stops are pivoted on the axis 8 and are adapted to be raised before the pin 9 of the stop rack 10 simultaneously with the operation of the punch connected with the raised stop. The stop bar unit 7 is a familiar part of the well known machine and is made so as to be removable and replaceable.

According to the present invention the stop bar unit 7 is provided with mechanism, 90 to be hereinafter described, by which the operation of any character key will cause the operation of the transfer signal producing member, that is, the "S" punch. Moreover, when the S punch is operated, as by 95 the depression of the space key, such operation will cause, according to the adjustment, the operation of a selected one of a plurality of unit stops. According to the construction shown, the lever 3 connected with the 100 S punch bar is connected at its other end with a vertically sliding member 16 having a socket 17 for the reception of the lever 3 and arranged to slide within the frame 7. This member 16 is rigidly connected with a 105 horizontal bar 12 also arranged to slide vertically and this bar is provided with a member 11 mounted thereon to slide in a horizontal direction. This member 11 is provided with projections 14 and 15, (Fig. 7) 110 which projections can be brought over the upper ends of different bars in the series 6 as desired. In the normal position of the member 11 in which the basic value of the 115 space is to be registered as four units, as shown in Fig. 2, the projection 14 is above the extended upper end of stop bar 18 connected with the four unit stop of the series of stops 5. In the abnormal position of the member 11, (shown in Fig. 4) the projection 15 is above the extended upper end of bar 22 connected with the seven unit stop. The bar 18 is returned to its initial position by a spring 19, one end of which 120 is secured to a lug 20 on the bar 18 and the other end to a stud 21 on the frame 7 (see Figs. 1, 3 and 7). The bar 22 has a shoulder 23 similar to the shoulder 23^a 125 shown in Fig. 8 upon which one of the levers 3 bears and this bar is returned to

130

initial position by a spring 24 similar to the spring 19.

When the space key 25 (shown in Figs. 10 and 11), is desired to be used in connection with normal spacing it may be constructed so as to be supported on a rod 26 by two levers 27 supporting at their lower ends a plate 28 on which is mounted a sliding plate 29 having a lug 30 to engage with the key 25 bar 32 to operate in the usual fashion a punch for producing a signal component indicating the six unit position of the matrix case. It will be understood that with this adjustment of the sliding plate 29 there is a corresponding adjustment of the member 11 so that (as shown in Fig. 2), the operation of the S punch producing the transfer component of the signal will cause the operation of the four unit stop. In other words, the combined signal will measure four units but will place the matrix case and normal mold dimensioning mechanism in six unit position, it being remembered that the transfer component of the signal will cause the casting machine to cast a type or space body by means of the combination of the normal and the justification mold dimensioning mechanism and that when this combination is used the cast is two units less than would normally be recorded by the keyboard.

The slide plate 29 is also provided with a lug 31 so that when adjusted from the normal dotted position of Fig. 11 to the abnormal full line position it will operate valve bar 33 to produce a signal component indicating the nine unit position of the matrix case. With this adjustment of the plate 29 the member 11 will be adjusted as shown in Fig. 4 and will couple the S punch through the members 16, 11 and 12 with the bar 22 and the seven unit stop of the series of stops 5.

A member 13 in the form of a plate is mounted in the frame 7 so that it can be vertically reciprocated by the coupling bars 6 pertaining to type or character signals. It is adapted to be coupled with plate 11 and bar 12 when justification is to be added to type signals and for this purpose it is provided with a hook 34 (Fig. 6) which is furnished with a slot or groove 35 into which the lug 36 on the plate 13 enters. The hook 34 passes up through a slot 37 in the underside of plate 11 and is in position to be engaged by the shoulder 38 on the plate 11 when the latter is moved to the position, (see Figs. 5 and 6), which it assumes when the transfer component is to be added to type signals.

In this position of the plate 11 the projections 14 and 15 thereon do not engage any of the bars 6. The bars 6 pertaining to type signals have a shoulder 40 (see Fig. 8) which projects over the upper side of the plate 13 so that when any one of these bars

is moved downward on the operation of a type or character key such bar carries with it the plate 13 and this plate through its hook 34 pulls the members 11 and 12 downward so that the punch representing the transfer component of the space signal is operated through the part 16 and its lever 3 and its signal is added to each type signal. In Figs. 5 and 6 the mechanism is shown in the position assumed after a type signal to which the justification is to be added has been produced by the depression of a type key.

To facilitate the adjustment of the plate 11 along the bar 12 there is provided on the outside of the frame 7 a sliding finger or thumb piece 39, (Figs. 1, 3, 7 and 8) connected with a block 41 slidably mounted in a slot 42 in the front plate of the frame 7.

Attached to the block 41 is a rib 43 which rests in a groove 44 in the plate 11 (Figs. 6 and 7). Co-operating with the finger piece 39 is a spring catch 45 adapted to engage with slots in the edge of the thumb piece at each position of adjustment of the plate 11 (Fig. 1).

To minimize the danger of damage to the parts and to prevent inaccurate adjustment of the plate 11, provision is made so that the adjustment can only be made when the stop bars are in initial position. For this purpose there is mounted in the top plate 46 of the frame 7 a block 47 (Fig. 9) which has a central groove 48. This block is so mounted that in the normal position of adjustment the projection 15 of the plate 11 travels down the side 49 of the block 47. In the abnormal position of adjustment the projection 15 passes down the groove 48; while in the position for adding justification to characters it travels down the side 50 of the block 47. When the parts are in initial position the projection 15 can pass between the top of the block 47 and the underside of the cover plate 46 permitting adjustment of the plate 11. In any other position adjustment of the plate 11 is prevented.

In order to insure that the plate 13 will not tilt particularly when it is operated by a stop bar 6 engaging at or near one of its ends, two levers 51 and 52 are pivoted at 53, 53 to the front plate of the frame 7 and have their arms 54, 54 pivotally connected with a bar 55 which rests under the overturned upper edge of the plate 13, while the other arms 56, 56 of the levers 51 and 52 are coupled together by a bar 57. A tension spring 58 has one of its ends connected to the arm 54 of the lever 51 and its opposite end to the arm 56 of the lever 52 so that when the bar 55 is pressed down by descent of the plate 13 and the levers 51 and 52 are turned on their pivots, the spring is extended; when the pressure of the bars 6 on the plate 13 is released the spring 58 will

return the plate to and maintain it in initial position.

The justification space number indicator 59, (Fig. 1), is operated with each space signal and when adding justification to characters. For this purpose there is provided, for co-operation with the rack 60, a spring controlled pawl 61 pivotally carried on a lever 62 fulcrumed to a stationary support at 63 and coupled by a link 64 to a lever 65 fulcrumed at 66. On the member 16 is an adjustable projection or 'lock' 67 connected with the member 16 by a neck portion 68 passing through a suitable channel in the side of the frame 7. This block 67 projects into the path of the lever 65 so that each time the member 16 descends the pawl 61 is operated to move the rack upward the extent of one tooth.

In operation, assuming normal conditions of a four unit basic value for the space signal, the space key will be adjusted as shown in dotted lines in Fig. 11, and the slide 11 will be adjusted as shown in Fig. 2. If now a character key is struck it will produce its signal in the usual fashion. If the space key 25 is struck it will operate key bar 32 to cause operation of the S punch to produce the transfer component of the space signal and also the six unit punch which punch will in the usual manner throw up the six unit stop. The operation of the S punch will move the parts 16, 12 and 11 downwardly, the projection 14 on the latter engaging with stop bar 18 to operate the four unit stop. The operation of the six unit stop will have no effect because it is behind the four unit stop or further away from the zero position of the unit rack. For what is herein called the abnormal condition in which the base value of the space signal is to be seven units, the space key 25 is adjusted as in full lines in Fig. 11, and the member 11 is adjusted to the position shown in Fig. 4. These adjustments will have no effect upon the operation of character or justification keys, but when the space key 25 is depressed it will operate key bar 33 which will cause the operation of the S punch producing the transfer component of the space signal and the nine unit punch to produce the dimension component of the space signal. The nine unit punch will operate in the usual fashion to throw up the nine unit stop. The S punch will operate the parts 16, 12 and 11 depressing them to the position shown in Fig. 4, in which position the projection 15 of the member 11 has operated the stop bar 22 and the latter has thrown up the seven unit stop. Under either condition, the parts 16, 12 and 11 and the operated stop bar are returned to initial position, when the space key is released, by the springs 19 or 24.

It will be seen that in the normal setting

the caster will receive a signal resulting in placing the matrix case in the six unit position, although the effective stop of the units measuring mechanism will be the four unit stop. In the abnormal adjustment the matrix case will be positioned in the nine unit position but the measure on the keyboard will be seven units.

When it is desired to add justification to types or characters, the slide 11 is moved to the position shown in Figs. 5 and 6, in which position it is connected by the hook 34 with the sliding plate 13. When a character key is struck its signal will be recorded in the usual fashion. The punch for recording the dimensioning component of that signal will not only throw up the stop measuring the value of that signal, but will also by the engagement of its shoulder 40 with the slide member 13, depress the latter thus causing the hook 34 to pull downwardly the slide member 11 and its associated parts 12 and 16 as shown in Figs. 5 and 6. The part 16 by engaging the walls of its socket 17 with the lever 3 connected with the S punch will cause the operation of the latter so that the combined signal produced is of three components, the positioning component, the dimensioning component and the transfer component. The depression of the part 16 will also cause the depression of the projection 67 and the latter acting upon the lever 65 and its associated elements will cause the space pointer 59 to move up one space, the action so far as the pointer 59 is concerned being the same as when, under any condition of adjustment, the space key is struck. Since the addition of the transfer component to type signals decreases the value of the signal by two units it is necessary to make good this deficiency through the medium of the justification signals, so that the operator having read the justification indicator must add two units to the justification fraction and operate the keys accordingly.

I claim:—

1. A typographic composing machine having incorporated therein devices for producing signals indicating "position," "dimension," and a "transfer" components, together with a plurality of units admeasuring devices, and in combination therewith a manually controlled coupling mechanism movable into positions to connect the transfer component signal producing device with one or the other of selected units admeasuring devices to operate the latter.

2. A typographic composing machine having incorporated therein devices for producing signals indicating "position," "dimension," and a "transfer" components, and in combination therewith a manually controlled coupling mechanism normally out of but movable into position to couple the

transfer signal producing device with the dimension signal producing devices whereby any one of the latter operates the former to produce a signal indicating the addition of justification to the type body.

3. A typographic composing machine having incorporated therein devices for producing signals indicating "position," "dimension," and a "transfer" components, together with a plurality of units admeasuring devices, and in combination therewith manually controlled coupling mechanism movable into positions to connect the transfer component signal producing device with one or the other of selected units admeasuring devices to operate the latter and also movable into position to couple the transfer signal producing device with the dimension signal producing devices, whereby any one of the latter operates the former to produce a signal indicating the addition of justification to the type body.

4. In a record strip composing or preparing machine provided with a units measuring mechanism comprising a series of stop bars, a series of signal producing devices including dimensioning signal producing members connected with said stop bars, and a transfer signal producing member, and in combination therewith an adjustable device for operatively connecting the transfer signal producing member with a selected stop bar.

5. In a record strip composing or preparing machine provided with a series of positioning and dimensioning component signal producing devices and a transfer component signal producing device and with a units measuring mechanism comprising a series of stops, and in combination therewith, an ad-

justable coupling device for connecting the transfer component signal producing device with a selected one of said stops.

6. In a record strip composing or preparing machine provided with a series of dimensioning component signal producing devices and a transfer component signal producing device and with a units measuring mechanism comprising a series of stops and a coupling unit for connecting said dimensioning component signal producing devices with their corresponding stops, and in combination therewith, an adjustable device mounted on the coupling unit for operatively connecting a selected one of said stops with said transfer component signal producing device.

7. In a record strip composing or preparing machine provided with a series of positioning and dimensioning component signal producing devices and a transfer component signal producing device, means for operating a positioning component device and a dimensioning component device from a type key, means for operating a dimensioning component device and the transfer component device from a space key, units measuring mechanism comprising a series of stop bars and stops coupled with the dimensioning component signal producing devices and a plurality of other stop bars and stops and in combination therewith, an adjustable device for operatively connecting selectively one or another of said other stop bars and stops or any one of said first mentioned series of stop bars and stops, according to the adjustment, with said transfer component signal producing device.

JOSEPH BOURDAS SMITH BOOTH.
